UNITED STATES PATENT OFFICE.

EDWARD F. GINGRAS, OF BUFFALO, NEW YORK.

PROCESS FOR MAKING BELTING.

1,419,842.

Specification of Letters Patent. Patented June 13, 1922.

Application filed September 4, 1918. Serial No. 252,634.

To all whom it may concern:

Be it known that I, EDWARD F. GINGRAS, of the city of Buffalo, in the county of Erie and State of New York, have invented certain new and useful Improvements in Processes for Making Belting; and I do hereby declare the following to be a full, clear, and exact description of my invention, such as will enable others skilled in the art to which it appertains to make and use the same, reference being had to the accompanying drawings, and to figures of references marked thereon, which form part of this specification.

15 Like figures of reference refer to like parts.

This invention relates to processes for making belting, such as are disclosed in my application filed on or about February 9, 20 1917, Serial Number 147,608, and renewed as Serial Number 358,131, filed February 12, 1920, of which application the present application is a continuation in part. The process constituting this invention is particularly applicable to fabric belting for transmission of power, with or without an added coating of leather or the like for a frictional surface, using the fabric for form and strength.

30 One of the objections by the trade to the use of some forms of fabric belting, is the failure of such belts to maintain their form after a little use, especially when such belts become longer on one edge than the other, 35 causing the belt to run to one side of the pulley. Wide flanged pulleys and guides have therefore been resorted to for keeping the belt from running off the pulleys, and this results in a quick abrasive destructing 40 of the edges of the belt. This destruction soon extends into the body of the belt, owing to additional strains accumulating from the loss of strength in the edges, much disqualifying the belt for transmission service.

45 Therefore, one of the objects of my invention is to provide such a process for treating fabric belts for use, whether for service with or without a frictioning surface, as will have an operation included 50 therein which will bring about the treatment of the entire belt under a like condition throughout its length at one time, to bring about a uniform modification of the original elastic properties of the fabric, whereby 55 the finished belt is properly conditioned, not only to resist further stretching in use,

but for the formation of a belt, which in practical use as a power transmission element, will retain the equality of its side dimensions, to balance the same, thus obviating the change above referred to in inferior belts, (where one side becomes longer than the other) and eliminating through the agency of my process the initial cause of the destruction of a treated belt.

60 A further object of the invention is to provide a process for treating the materials for making up the belting to adapt the same for use therein, using cotton or other fabric in connection with pieces of old worn belts or leather to form a continuous, practical and durable belt at a cost less than that of new leather belt, of the same size and strength.

65 Another object is to provide a process which will include the preparation of the fabric under tension and also the preparation of old leather to make these two materials serviceable for use in making of the compound belting.

70 With these and other objects my invention consists in certain operations which are carried out upon suitable apparatus for making up the compound belting. One such set of appliances used for carrying out this process is illustrated in the accompanying drawings, which are hereinafter described, the application of the process thereto is explained and what I claim is set forth.

75 In the drawings.

Figure 1 is an elevation showing a mill room equipped with apparatus adapted to the purpose of my process of preparing the belting parts and making of the belting.

Figure 2 is a plan of the apparatus shown 80 in Figure 1.

Figure 3 is a perspective view of the saturating tank of the apparatus.

Figure 4 is a sectional side elevation of 85 part of said saturating tank.

Figure 5 is an elevation of one of the roller suspension members with roller attached.

Figure 6 is a section view of a roller end 90 showing the rod upon which the roller is journaled with an elbow bracket attached.

95 The figures in detail show two posts 1 and 2 between which the apparatus is assembled on the floor 3. The apparatus includes a saturating tank 4, a pulley carriage 5, a fixed windlass 6, a press 7 and pulleys 8, 9 and 10 journaled in hangers, fixed to walls, ad-

ja cent the posts 1 and 2, as shown. The tank 4 is mounted upon rollers 4^a, 4^a and has suspended beneath it a gas burner 11, having a valve 12. Suitable flexible connections with a gas supply are provided, but not here shown which permit of positioning the tank 4 in and out of use. Upon the ledge 4^b of the tank 4 are fixed wringer blocks 13 and 14, in which is journaled the wringer roller 15. The block 13 is connected by the hinge 15^a to the upright guide 16, in which is fitted, for reciprocation, the block 17. A screw crank 18, attached to the block 17 and threaded in the guide 16, positions the block 17. To the block 14 is hooked the upright guide 19, in which is fitted, for reciprocation, the block 20. A screw crank 21, attached to the block 20 and threaded in the guide 19, positions the block 20. Journaled in the blocks 17 and 20 is a roller 22, which is forced against the roller 15 by means of the screw cranks 18 and 21, when the hooks 23, 23, on opposite sides of the upright 19, engage their pins 24, 24. Beneath the wringer, and releasably fixed by pins 25, 25, in the brackets 26, 26, is a scraper bar 27.

Mounted upon the ledge 4^b, of the tank 4, are four bearings 28, 28 and 29, 29. In the bearings 28, 28 are journaled the stub shafts 30, 30 of the suspension members 31, 31, each comprising a T-piece 32, to which is fixed a stub shaft 30. Also fixed to the T-piece 32 is cylindrical piece 33, upon which is journaled another T-piece 34, held thereon by the cap 35. To the T-piece 34 is fixed the L-piece 36, positioned to have its end 37, bear upon the ledge 4^b. Depending from and fixed to the T-piece 32 is a long piece 38, at the lower end of which is fixed a strap clamp 39, having also fixed therein the roller bracket 40. Bolts 41, 41, 41 draw the clamp parts together to grip the piece 38 and the bracket 40. In the brackets 40, 40 is threaded a rod 42, upon which is journaled a roller 43. A similar set of parts comprise the suspension members 44, 44, journaled on the bearings 29, 29, and supporting the roller 45. Journaled in blocks 46, 46, fixed to the ledge 4^b, is a roller 47, which completes the tank device, except for a pulley 48, fixed to the shaft 49, of the wringer roller 15. The pulley 48 is connected by belt 50 to the pulley 51, fixed upon a line shaft 52, journaled in the hanger 53, fixed to the beam 54. The broken line 50^a represents a crossed position of the belt 50. Adjoining the tank 4 is the pulley carriage 5, having a frame 54 mounted upon rollers 55, 55. The frame 5^a has journaled upon it two small pulleys 56 and 57 and one large pulley 58. To an extension 59, of the frame 5^a, are fixed two cables 60, 60 attached and wound upon a shaft 61, journaled in the frame 62, of the windlass 6. Gearing 63 is attached to the

shaft 61 and the shaft 64 of the crank 65, for winding the cables 60, 60. Two rollers 66 and 67 are journaled upon the frame 62. The press 7 has an open space in the standard 68 for the passage of the belt 69, which is shown passing above, between the adjustable plate 70 and the table 71. The hand wheel 72, with the usual threaded shaft 73, fixed thereto.

In operating the apparatus to carry out my process, one or more belts, such as 74, 75 and 76 of the group 69, are passed over the pulleys and threaded through the various devices as follows: starting at, say pulley 10, the belts pass between the table 71 and the plate 70 of the press 7, thence over pulleys 67, 57 and around pulley 9. Returning it engages pulley 58 of the pulley carriage 5 and passes back toward the column 1, around pulley 8 and over roller 47 passing down into the tank 4, under roller 43, around roller 45, up over the edges of the scraper bar 27, to between the wringer rollers 15 and 22. From there it passes over pulleys 56 and 66 back to pulley 10, there being joints somewhere in the belts, to make them continuous.

A solution of gelatinous substance with suitable ingredients, partially fills the tank 4 and through which the group of cotton belts is slowly passed to become thoroughly saturated.

The windlass 6 is operated to pull the cables 60, 60 and draw the pulley carriage 5 in a manner to have the pulley 58 tighten the belts. During tension on the belts, the rollers 43 and 45 are drawn toward one another, but the suspension members 31 and 44 are prevented from turning in their respective bearings 28 and 29, by the L members 36, 36 bearing upon the tank ledge 4^b. The course of the belts through the tank 4 is shown in the Figure 3 by the dot and dash line S. The wringer is operated by pulley 48, turned by belt 50 from the pulley 51 on the driving shaft 52. The scraper bar 27 rids the belts of part of excess solution and the remainder is squeezed out between the rollers 15 and 32. The tank solution is heated by the gas heater 11, if desired.

The belts are removed from the tank 4 by first unhooking the upper part 19 of the wringer and swinging the roller 22 up out of the way. The pins 25, 25 are next withdrawn and the scraper bar 27 is removed. Next the L members 36, 36 are swung at right angles to the side of the tank 4 and the rollers 43 and 45 are swung upward as is shown for roller 43 of Figure 4 through the path P to the position 43^a. One of the clamps 39, on each suspension member 31 and 44, is next detached from the bracket 40 and the rollers 43 and 45 are swung up, turning on the clamps at the opposite ends of these rollers, freeing the belts. The

pulley carriage 5 is next drawn further away from the tank 4 to take up the slack in the group of belts 69 and to put them under tension to stretch them and hold them 5 in this stretched condition until dried out. During the drying process the belting 69 may be drawn around the pulleys 8, 9 and 10 as desired. After the belts have dried and tension is maintained thereby leather, 10 which has been previously cleansed and cut to desired thickness and width, is cemented intermittently to one surface of the belts and is fixed thereon in the press 7 and held until the cement is set. Scarf joints are 15 made between adjoining pieces of leather on the cotton so as to present an even surface for contact with pulleys in use. This process of covering the belts with pieces of leather is continued until the whole of the 20 belts are covered on one side when they are cut through and removed from the apparatus and rolled up for delivery.

Cotton belting can be thus treated in this apparatus, omitting the leather coating and 25 when a suitable solution is used to saturate the cotton, the belt produced will be ready for use as a treated and properly stretched cotton belt, or if desired an additional coating can be applied to one side, or both sides 30 of the treated cotton belt to increase its frictional qualities.

Belts produced by this process, and especially carried out on the said apparatus as above described and explained, are found 35 to run straight and give service equal to if not better than an all leather belt of the same strength.

Having described my invention, I claim—

1. A process of making belting from an 40 endless belt of flexible material consisting in treating said material with a gelatinous solution, placing it under a stretching tension and holding it under such tension until dried.

45 2. A process of making belting from an endless belt of flexible material consisting in treating said material with a gelatinous solution, placing it under a stretching tension and holding it under such tension until dried so as to counteract the natural tendency of such to contract while drying.

3. The process of making belting from a 50 fabric belt consisting in applying a solidifying solution to said belt and of tensioning the belt and holding the same in a tensioned condition while said solution is solidifying, whereby the said belt is given a uniform and permanently fixed stretched condition, and shifting the belt longitudinally while the 55 solution is solidifying and while the belt is under tension.

4. The process of making belting from a 60 fabric belt consisting in applying a solidifying solution to said belt, of tensioning the belt and holding the same in a stretched con-

dition under the influence of force equally distributed throughout the length of said belt, while said solution is drying, and shifting the belt longitudinally while said solution is solidifying, during the tensioned condition of said belt, whereby a belt, having a uniform and permanently fixed stretched condition, is derived. 70

5. The process of making belting from a 75 fabric belt consisting in saturating said belt with a cementing solution and of tensioning the entire saturated belt at one time and holding the same in a tensioned condition while the said solution is drying, whereby the belt is given a uniform and permanently 80 fixed stretched condition throughout its entire length without changing the parallelism of the longitudinal edges of the belt.

6. The process of making belting from a 85 fabric belt consisting in saturating said belt with a cementing solution and of tensioning the entire saturated belt at one time and holding the same in a tensioned condition while the said solution is drying, and shifting the saturated belt while the solution is 90 drying and while the belt is in a tensioned condition, whereby the belt is given a uniform and permanently fixed stretched condition throughout its entire length without changing the parallelism of the parallel 95 edges of the belt.

7. The process of making belting from a 100 fabric belt consisting in applying a solidifying solution to said belt and of tensioning the belt and holding the same in a tensioned condition while the said solution is solidifying and shifting the belt longitudinally while the solution is drying on said belt and while the belt is in a tensioned condition and without removing the tension from the belt, 105 whereby said belt can be changed in position for free access of air to all parts thereof during the drying of the same.

8. The process of making belting from a 110 fabric belt consisting in applying a solidifying solution to said belt and of tensioning the belt and holding the same in a tensioned condition while the said solution is solidifying and of fixing a frictioning surface to one side of said belt during its tensioned condition and without removing the tension. 115

9. The process of making belting from a 120 fabric belt consisting in applying a solidifying solution to said belt, of tensioning the belt and holding the same in a stretched condition under the influence of force equally distributed throughout the length of said belt, while said solution is drying to give said belt a uniform and permanently fixed stretched condition, and of fixing a frictioning surface to one side of said belt while the same is held stretched by force. 125

10. The process of making belting from a 130 fabric belt consisting in applying a solidifying solution to said belt and of tensioning

the belt and holding the same in a tensioned condition while the said solution is solidifying, and shifting the belt longitudinally while the solution is drying and 5 without removing the tension and of fixing a frictioning surface to one side of said belt while the same is in a stretched condition and without removing the tension.

11. The process of making belting from a 10 fabric belt consisting in saturating said belt with a cementing solution and of tensioning the entire saturated belt and of holding the same in a tensioned condition while the said solution is drying and shifting the belt longitudinally and applying a frictional surface to the same without removing the tension.

12. A process of making belting from belting consisting in saturating a fibrous 20 belt with a cementing solution, removing the excess of the solution from the belt, then stretching said saturated belt and holding

the same in a stretched condition until the cement has set, then cementing friction material intermittently to said belt, and forcefully pressing said material to said belt. 25

13. A process for making belting by affixing facing material to an endless belt of flexible material consisting in supporting the flexible material so that it may be shifted 30 longitudinally, subjecting it to tension, and, while still under tension, adhering the facing material thereto.

14. A process for making belting by affixing facing material to an endless belt of flexible material consisting in supporting the flexible material so that it may be shifted 35 longitudinally, subjecting it to tension, saturating it with a gelatinous solution, stretching it and holding it in its stretched condition until dried out, and while still so held adhering the facing material thereto.

Buffalo, N. Y., August 29, 1918.
EDWARD F. GINGRAS.
